BRANCH FOR AN ARTIFICIAL TREE OR
SIMILAR ARTICLE

Joseph T. Gelardi, Yonkers, N.Y., assignor to American
Technical Industries, Inc., Mount Vernon, N.Y.

Continuation of design application Ser. No. 2,411, June 18,
1968. This application Nov. 5, 1969, Ser. No. 19,958

Term of patent 14 years

Int. Cl. D11—04

U.S. Cl. D29—1

FIG. 1

FIG. 2

FIG. 3

FIG. 1 is a top plan view of a branch for an artificial tree or similar article showing my new design, the branch is broken away for convenience of illustration;

FIG. 2 is a fragmentary view thereof with the rib removed and in a flattened condition; and

FIG. 3 is a perspective view on a reduced scale of the branch for an artificial tree or similar article.

This application is a continuation-in-part of Ser. No. 2,411, filed June 18, 1968, now abandoned.

I claim:

The ornamental design for a branch for an artificial tree or similar article, as shown and described.
